PRICE TAG HOLDER

Filed Aug. 28, 1930

FIG. 1.

FIG. 2.

FIG. 3.

John P. Siebe, Inventor
A. F. Kauder, Jr., Attorney

UNITED STATES PATENT OFFICE

JOHN P. SIEBE, OF SACRAMENTO, CALIFORNIA

PRICE TAG HOLDER

Application filed August 28, 1930. Serial No. 473,415.

The invention relates to devices for holding price tags on articles of merchandise and has for its object the provision of a price tag holder including a frame having means to 5 removably support a price card or the like, and provided with means adjustably mounted on the frame to hold the frame and the price card on the article of merchandise.

A further object of the invention is the 10 provision of a price tag holder consisting of a plate of sheet metal provided with means to hold a price tag thereon, and means slidably engaging side members on the plate and adapted to clamp an article of merchandise 15 therebetween and support the plate in position.

A further object of the invention is the 20 provision of a price tag holder comprising a plate of sheet metal having its edges turned and spaced from the plate to provide means to support a price card, the plate having cut out portions forming tongues bent back on the plate and spaced therefrom intermediate 25 of their ends to provide guides to slidably engage rods to hold them adjustably on the plate to clamp an article of merchandise therebetween and hold the plate supported thereon.

The invention will be described in detail 30 hereinafter and will be found illustrated in the accompanying drawings, in which

Figure 1 is a view in perspective of the improved price tag holder showing it applied to an article of merchandise,

Figure 2 is a top plan view of the price tag holder,

Figure 3 is a rear view in elevation, and

Figure 4 is a transverse sectional view on a plane indicated by the line 4-4 of Figure 3.

In the drawings similar reference characters are used to designate corresponding parts throughout the several views.

The price tag holder, as illustrated in the 45 drawings, comprises a plate 1 having its bottom and end edges returned on the plate as shown at 2 and 3 respectively, the returned portions being spaced from the adjacent surface of the plate to provide means for supporting a price card or tag 4. The body of

the plate is provided with integral tongues 5 and 6, formed by cuts made in the plate and bent upwardly as shown, said tongues being spaced apart. Intermediate of the tongues 5 and 6, the plate is provided with a 55 tongue, also formed by cutting the plate, said tongue being bent downwardly and located between the tongues 5 and 6. The tongues 5, 6 and 7 are each provided with an outwardly bent portion 8, intermediate of the 60 ends of each tongue, said outwardly bent portions being alined and providing guides for rods or wires 9, said rods or wires being slidable in said guides, one end of the rods being shaped as shown at 10 to engage 65 opposite sides of an article of merchandise designated A, while the other ends of the rods are provided with outwardly bent flanges forming lugs or stops, as indicated at 11, to limit the movement of said rods into merchandise engaging position, and to prevent the rods from inadvertently sliding out of the guides 8.

By providing the upwardly bent tongues 5 and 6, and the downwardly bent tongue 7 intermediate of the tongues 5 and 6, it will be apparent that the portions of said tongues integral with the plate provide means by which the rods or wires 9 are held from lateral movement relatively to the tongues and are securely held in adjustable position on the plate. The ends 10 of the wires or rods are shown in the drawings to be substantially at right angles to the rods, this structure being adapted to secure the price tag holder on a rectangular package of merchandise. It will be understood, however, that the ends 10 may be shaped otherwise for securing the holder to articles of different shapes.

What is claimed is:—

1. A price tag holder, comprising a plate of sheet metal having means to hold a price card, rods slidably mounted on said plate and adapted to engage an article of merchandise to hold the plate in position thereon, and guide means on said plate enclosing and slidably mounting said rods for adjustment relatively thereto.

2. A price card holder, comprising a plate of sheet metal having means to hold a price

100

- card, tongues formed in the plate by incisions made therein, said tongues being folded on the plate and spaced therefrom intermediate of their ends providing guide loops, and rods 5 slidably mounted in said guide loops and adjustable therein to engage an article of merchandise to hold the plate in position thereon.
3. A price tag holder, comprising a plate of sheet metal having means to hold a price 10 card, tongues formed on the plate by incisions made therein, said tongues being arranged in staggered relation, folded on the plate in opposite directions alternately and spaced from the plate intermediate of their ends to 15 provide guide loops, and rods slidably mounted in said guide loops and adjustable therein to engage an article of merchandise to hold the plate in position thereon.
4. A price tag holder, comprising a plate 20 of sheet metal having means to hold a price card, tongues formed on the plate by incisions made therein, said tongues being folded on the plate and spaced therefrom intermediate of their ends providing guide loops, rods 25 slidably mounted in said guide loops and adjustable therein to engage an article of merchandise to hold the plate in position thereon, and stops on said rods to limit the movement of the rods relatively to the guide 30 loops.

In testimony whereof I affix my signature.
JOHN P. SIEBE.
